UNITED STATES PATENT OFFICE.

LEWIS C. BAYLES AND CHARLES C. HANSEN, OF EASTON, PENNSYLVANIA, ASSIGNEES
TO INGERSOLL-RAND COMPANY, OF JERSEY CITY, NEW JERSEY, A CORPORATION
OF NEW JERSEY.

DUSTLESS ROCK DRILL.

Application filed February 28, 1924. Serial No. 695,622.

This invention relates to fluid actuated rock drills particularly of the hammer type, provided with a hammer piston having a head and a forward fluted shank reciprocating in a cylinder, for imparting blows of impact to a hollow drill steel through which cleansing fluid, as water or air and water, is supplied to the drilled hole.

In those cases in which objectionable fogging and dust might be created by the intermingling of the air and water for cleansing the hole, provision may be made for preventing air from passing along the flutes of the piston shank to the front head cavity and thus mingling with the water.

The object of the present invention is to prevent air from passing along the flutes of the piston shank by means of a sealing member or members which form part of the front cylinder washer and do not require reconstruction of a standard rock drill for the insertion of the new parts.

The seal of the piston flutes may be a metal to metal seal between the flutes and a metal sealing member and in some instances an additional packing or cup leather is provided. In carrying out the invention, the front cylinder washer comprises a plurality of metal parts through which the piston shank passes, the main part of the washer preferably being stationary in the front end of the cylinder, and another auxiliary part of the washer forming a sealing member fluted to correspond with the piston shank and adapted to rotate with the piston relatively to the stationary part. The rotating part of the washer may be transversely divided and the additional packing member may be located between the said divided parts.

One of the advantages of this construction resides in the fact that the dust preventing devices may be readily applied to standard drills of the "Leyner" type using a so called short piston, without changing the piston.

The invention is shown in its preferred form in the accompanying drawings, in which

Figure 1 is a longitudinal sectional elevation of a rock drill of the type known as the "Leyner".

Figure 2 is a detail longitudinal sectional view of one part of the front cylinder washer,

Figure 3 is a detail perspective view of another part of the washer,

Figure 4 is an enlarged detail longitudinal sectional view of another form of the rotatable part of the washer,

Figure 5 is a detail perspective view of the fibrous packing or cup leather for the washer,

Figure 6 is an enlarged detail longitudinal sectional view of a modified form of the rotatable part of the washer,

Figure 7 is a perspective view of another form of packing or cup leather,

Figure 8 is a detail longitudinal sectional view of a modified form of the rotatable part of the washer,

Figure 9 is a longitudinal sectional elevation of a portion of a rock drill equipped with the rotatable parts and the cup leather illustrated in Figures 4 and 5, and

Figure 10 is a view similar to Figure 9 in which the rock drill is equipped with the rotatable parts and the cup leather illustrated in Figures 6 and 7.

Referring to the drawings, the cylinder A is provided with a main bore B and a forward bore C of smaller diameter, which latter bore may be formed by the front cylinder washer having the main stationary part or member D and the auxiliary part D', the latter being rotatable relatively to the main part D for the purposes herein-after more fully described.

A piston E is adapted to reciprocate in the cylinder and is provided with a forward extension F fitting the bore C of smaller diameter. A hollow drill steel G is carried in the usual manner by the forward end of the machine, and extends into the machine to a position to receive the impact of the blows of the piston. A water tube H extends longitudinally through and approximately fits a hole in the piston, and is adapted to deliver water to the drill steel.

Motive fluid is supplied to the machine through the inlet J controlled by a suitable throttle of which the controlling handle K only is indicated. A suitable fluid distributing valve may be provided in the valve chest L, but as the distribution of motive fluid to the cylinder forms no part of the present invention, the details of such construction are not indicated. The piston is provided with a rifle nut O cooperating with the rifle bar P and the usual back head is

indicated at Q, having the water connection R. The parts of the machine are held together by the usual side bolts S, a portion of one side bolt being shown.

5 Any suitable and usual front head construction for the machine may be provided, and in this instance the front head T is provided with the front head cap U in which is located the chuck key V. A chuck nut W, 10 is threaded to the chuck X and within the chuck are located the chuck front bushing, Y and the chuck back bushing Z.

So far described, the machine is like a standard "Leyner" drill, except that the 15 flutes a on the piston shank F are shown extending substantially the entire length of the shank although they need only extend for a portion of the shank leaving the remainder of the shank smooth as usual. The 20 piston is of the ordinary standard length.

In accordance with our invention, the 25 front cylinder washer D in Figure 1 is provided with the rotatable auxiliary part or member D' formed with the flutes b to conform to the flutes a of the piston shank. The fluted rotatable member D' preferably forms a substantially close fit with the flutes a of the piston shank, so that there is a metal to metal seal between these parts 30 which prevents air in any appreciable quantity from passing along the flutes to the cavity of the front head. In order to permit any air which may leak between the member D' and the front cylinder washer D to pass 35 to atmosphere, the member D' is preferably provided with an annular external groove c and the stationary front cylinder washer member D and the drill cylinder are provided with apertures d and e respectively, 40 communicating with the groove c and forming vents. To further provide for leakage, a vent f from the chuck cavity permits any air which would otherwise pass to the drill steel, to be vented to atmosphere.

45 In the modification of the invention shown in Figures 4, 5 and 9, the rotatable part D² which may be inserted in the front cylinder washer D to rotate with the piston, is divided into two parts g and h, and the fibrous packing which may be in the form of a cup 50 leather j, is located between the two parts g and h and is constructed to conform to the flutes of the piston shank, as illustrated particularly in Figure 5, so that the packing 55 or cup leather extends rearwardly along the piston shank and forms an additional seal for the flutes of the piston shank. The part g is preferably under-cut at k, as shown to accommodate the cup leather j.

60 In the modification shown in Figures 6, 7 and 10 the rotatable part D³ of the front cylinder washer is also divided into sections o and p and the packing or cup leather q located between the sections o and p. In this

case the cup leather q is pressed or otherwise formed so that the corrugations or flutes r of the cup leather embrace and extend along the flutes of the piston shank an appreciable distance.

In the modification shown in Figure 8, 70 the rotatable part D⁴ of the front cylinder washer is not divided, but one end is undercut at s to accommodate the cup leather j like that shown in Figure 5.

75 We claim:

1. The combination of a fluid actuated rock drill having a cylinder, a reciprocating piston having a head and a forward fluted shank, a front cylinder washer having parts adapted to be inserted in the washer to rotate therein, said parts being fluted to cooperate with the flutes on the piston shank, and a fibrous packing between the said parts conforming to the flutes of the shank for preventing leakage of motive fluid along 85 the piston flutes to a drill steel.

2. The combination of a fluid actuated rock drill having a cylinder, a reciprocating piston having a head and a forward fluted shank, a front cylinder washer in the cylinder having two parts adapted to be inserted in the washer to rotate therein, said parts being fluted to cooperate with the flutes on the piston shank, a fibrous packing held between the parts and formed to cooperate 90 with the flutes of the shank for preventing leakage of motive fluid along the piston flutes to a drill steel and rotatable with said shank, an annular external groove on said parts, and passages leading from said groove to the atmosphere to conduct motive fluid leaking between the piston shank and the front cylinder washer to the atmosphere.

3. The combination of a fluid actuated rock drill having a cylinder, a reciprocating piston having a head and a forward fluted shank, a front cylinder washer encircled by the cylinder having two parts adapted to rotate in the washer, said parts having flutes to cooperate with the flutes on the piston shank, a cup leather held between said parts and having a rearwardly extending portion constructed to conform to the flutes on the piston shank for preventing leakage of motive fluid along the piston flutes to a drill steel, said cup leather being rotatable with said shank, an external annular groove on said parts to receive motive fluid leaking between the piston shank and the front cylinder washer, and passages through the cylinder and the front cylinder washer communicating with said groove to permit the escape of leakage motive fluid from the groove to the atmosphere.

105 In testimony whereof we have signed this 125 specification.

CHARLES C. HANSEN.
LEWIS C. BAYLES.
